25 Fig. 9. Serrulata & sancta.

UNITED STATES PATENT OFFICE.

MORRIS FALK, OF LEOMINSTER, MASSACHUSETTS.

LOCK.

1,237,932.

Specification of Letters Patent. Patented Dec. 17, 1917.

Application filed June 27, 1913. Serial No. 242,256.

To all whom it may concern:

Be it known that I, MORRIS FALK, a citizen of the United States, residing at Leominster, in the county of Worcester and State of Massachusetts, have invented a new and useful Lock, of which the following is a specification.

The principal objects of this invention are to provide a lock which cannot be picked or unlocked by the ordinary means used by burglars, and it involves the provision of a practical construction of bolt which will have no slanting end that can be pushed back by transverse pressure. The invention also involves a very simple arrangement for operating such bolt and a circular form of bolt with a concentric operating rack upon it.

Another object of the invention is to provide a simple and convenient construction by which the key inserted from the outside can ordinarily lock and unlock it and which can be changed very readily from the inside so that without unlocking the lock it can be prevented from being unlocked from the outside although controlled fully from the inside at that time.

The invention also involves improvements in details of construction and combinations of parts for the purpose of simplifying and improving, and especially rendering more safe locks of this type.

Further objects and advantages of the invention will appear hereinafter.

Reference is to be had to the accompanying drawings, in which—

Figure 1 is an elevation of a preferred embodiment of this invention shown in the form of a lock with the front plate removed, and the door and casing being shown in section, the parts being shown in unlocked position;

Fig. 2 is a similar view but showing the parts in locked position;

Fig. 3 is a sectional view on the line 3—3 of Fig. 1 showing not only the parts illustrated in Fig. 2, but also the key-receiving part of the device extending to the outside of the door;

Figs. 4 and 5 are sectional views on the line 4—5 of Fig. 3 showing certain details in two different positions;

Fig. 6 is a side view of a reciprocable member controlling the connection of the key with the lock;

Fig. 7 is a similar view of the inside knob;

Fig. 8 is a similar view of the operating gear;

Fig. 9 is a similar view of the plate for operating the gear; Figs. 6, 7, 8 and 9 being located in axial alignment with each other to show how these four parts go together, and

Fig. 10 is a sectional view on the line 10—10 of Fig. 1, showing the hasp with 65 which the lock is adapted to coöperate.

I have shown the invention as applied to a heavy door 10 and as designed to lock this door to the casing 11 which has a plate 12 bent down at the edge 13 and provided with 70 a pair of U-shaped hasps 14 riveted thereto, although the invention is not limited to the use of two of these.

The door is perforated for the usual key-receiving element, such as a pin tumbler 75 cylinder 20 which is adjustably connected with a sheet metal cover plate 21 by means of two bolts 22 and adjusting nuts thereon, the screws passing through bosses projecting from the pin cylinder. These screws are 80 fixed to the sheet metal plate 21. The construction of the interior of the pin cylinder 29 is not shown herein, as it forms no part of this invention. Any device for this purpose can be employed in connection with 85 this apparatus. It will be sufficient to say that when the proper key is inserted, it is capable of oscillating a non-circular bar 23 which projects through the plate 21 into the lock proper which is formed between the 90 plate 21 and a hollow metal member 24, these two constituting the lock casing.

The bar 23 projects into a slot 25 shaped to fit it and formed in the center of a circular oscillatable plate 26 located inside the 95 lock casing. A spring 27 acting against the casing cover 21 or a washer 28 therein presses the plate 26 whenever possible into a sunken circular seat 29 in the flat surface of a circular operating member 30. This is 100 shown in the form of a gear and has a circular groove 31, and the plate 26 has a pin 32 extending into the groove when the plate is in the position shown in Fig. 3. This groove is shown as provided with stops 34 105 which in this case are simply the ends of the groove itself, although these stops may be made in any desired way, but they are located in such position that, when the key is turned and the bar 23 with it, the plate 110 also will be turned and at a certain position will take the gear 30 and turn that with it,

The gear 30 is mounted on and fixed to the shank 33 of an internal knob 35. The shank of this knob extends through a circular hole in the cast casing 24 and the gear 5 is splined to it. The gear has a hub 36 which, when the parts are assembled, abuts against the inside surface of the casing 24 and holds the parts 30 and 35 against relative longitudinal motion, but they are capable of rotating in the bearing formed for the shank 33. The knob 35 has a knurled surface by which it is adapted to be manipulated and it will at all times turn the operating gear with it. It cannot be disconnected from it after the lock is set up and assembled.

The shank 33 is provided with a slot 37 extending in from one side, and the hub 36 also has a passage 38 registering with the slot 37, this passage being formed under an extension on the hub which fits against the inner wall of the casing 24. This slot and passage are bounded by the walls of the solid portions of the hub and shank respectively and are provided for the purpose of admitting the end of an arm 39. This arm is pivoted at 40 on the casing, and a spring 41 always presses it inwardly toward the center of the rotating elements 30 and 35. A pin 42 on the rear of the gear 30 is adapted to engage this arm 39 when the parts move around to the position shown in Fig. 5 and push it out against the action of the spring. Another pin or shoulder 43 acts on it when the gear turns backward to its extreme position to again push it out, but at other times the spring holds it in the position shown where the end 45 of the arm 39 projects through the slot 31 and space 38 where its end bears on the large cylindrical surface of a plunger 47. If the plunger is pushed in the end 45 will spring into the circular groove 46 on the plunger 47. This prevents longitudinal motion of the plunger. This plunger has a shoulder at 48 and the knob 35 is provided with a shouldered passage inside for receiving it. The extreme position of it is shown in Fig. 3. The end of the bar 23 always enters a slot in the end of the plunger and the spring 27 always tends to push the plunger out.

On account of the pin 42 and shoulder 43 the arm 39 is pushed back at the two extremes of the oscillating stroke of the operating gear so that the projection 45 is withdrawn from position to enter the groove 46. At that time the plunger 47 can be pushed in in the direction of the arrow in Fig. 3 and then its end which engages the under side of the plate 26 pushes it back against the action of the spring 27 so that its pin 32 will be withdrawn from the groove 31 and it will be rendered inoperative. Unless the knob 35 remains in one or the other extreme

position the end 45 immediately comes back into the groove 46 and holds the plunger and plate back so that the lock cannot be operated by the key. The lever 39 can be displaced only by turning the knob to extreme position. When the parts are in that position the gear 30 cannot be operated from the outside by means of the key, but it can be operated still as usual by the knob 35.

The rest of the lock consists of a stationary cylinder 50 constituting part of the casing and preferably integral with it and a cylindrical bolt 51 rotatably mounted upon it. The casing is provided with a semi-circular recess 52 for receiving the circular bolt. This bolt is provided with a notch at 53 for receiving the hasp 14 as shown in Fig. 1. The bolt is provided on the back with a gear segment 54 meshing with the gear 30. In order to limit the operation of the bolt a stop is provided by discontinuing the teeth so that the surface 55 of the last tooth on each side constitutes this stop.

For the purpose of still more securely holding the door, I have duplicated the bolt 51 by providing one exactly like it numbered 56, and located adjacent to it. It has its gear of course on a different portion of its circumference, because it meshes with the gear 30 at a different point in the circumference of that, but otherwise it is the same. It will be understood, of course, that these gears are held in place simply by securing the cover plate 21 on the casing 24.

In the operation of the device the plunger 47 being in the position shown in Fig. 3 the operator can insert the key from the outside and turn the bar 23 which will turn the plate 26. The pin 32 on that plate will at a certain point in its rotation engage one of the shoulders 34 and turn the gear 30 in one direction, that is, either lock or unlock the device. This turning motion is transmitted directly to the gears or bolts 51 and 56, and they will turn to the position shown in Fig. 1, or to that shown in Fig. 2 as desired. Prior to this time, the projection 45 extends into the slot 46 in position to hold the plunger 47 if it is pushed in. But whenever the lock is fully locked or unlocked, the pin 42 or shoulder 43 as the case may be, will engage the arm 39 and push it back so that its end 45 will be drawn up out of reach of the groove 46. Now the plunger 47, if already pushed in will be pushed back by the action of the spring 27 and the plate will move with it so that the key control of the lock will be no longer inoperative.

It will be seen therefore that this lock provides a safe construction which cannot be picked by inserting an implement between the door and the casing, and simply pressing on a slanting surface, as is the case

with many kinds of locks. The end of the bolt which holds the parts in position is concealed within the lock casing whenever it is locked, and cannot be tampered with from the outside. Furthermore, a very simple and convenient arrangement is provided by which the lock may be manipulated from within at all times and can be disconnected from the key-receiving portion of it so that it cannot be unlocked from the outside. At the same time the parts are reduced to a very simple construction with an increase in their strength and efficiency, and there are practically no parts that are likely to get out of order. They can be made of any desired strength without greatly increasing the size of the lock and are of extremely durable construction.

Although I have illustrated and described only a single form of the invention and shown it as applied to a double bolt lock, I am aware of the fact that many modifications can be made therein without departing from the scope of the invention as expressed in the claims.

Therefore I do not wish to be limited to this particular embodiment of the invention, but what I do claim is—

1. In a lock, the combination with a casing and a key-receiving element having means extending into the lock casing for operating the lock bolt, of a knob on the other side of the lock bolt casing having means for controlling the lock bolt at all times, and means within said knob adapted to be moved to two positions for disengaging the key-controlled means from the lock bolt.

2. In a lock, the combination with a casing and a key-receiving element having means extending into the lock casing for operating the lock bolt, of a knob on the other side of the lock bolt casing for controlling the lock bolt at all times, and means for disengaging the key-controlled means from the lock bolt when the lock bolt is in either extreme position.

3. In a lock, the combination with a casing, a bolt therein, and a key-receiving element, of a rotatable member inside the casing for operating the bolt, a plunger, and means whereby the plunger will disconnect the key-receiving element from said rotatable member and prevent the bolt being operated by a key.

4. In a lock, the combination with a casing, a bolt therein, and a key-receiving element, of a rotatable member inside the casing having means for operating the bolt, a knob on the other side of the casing positively connected with said rotatable member, a plunger centrally mounted in the knob, and means whereby the plunger will disconnect the key-receiving element from said rotatable member and prevent the bolt

being operated by a key from the other side.

5. In a lock, the combination with a casing, of a knob on one side of the casing, a gear in the casing fixed with respect to the knob and rotatable with it, said gear having a circular seat in its opposite face, a plate located in said seat, means on the plate by which a motion of rotation imparted to it will be imparted to the gear throughout a portion of its rotation, said plate being displaceable so as to lose control of the gear, a plunger located in the knob and projecting from its outer surface adapted to engage the plate and push it out of operative position, and key-controlled means for turning said plate.

6. In a lock, the combination with a casing, of a gear in the casing having a circular seat in its face, a plate located in said seat, means on the plate by which a motion of rotation imparted to it will be imparted to the gear throughout a portion of its rotation, said plate being displaceable so as to lose control of the gear, a plunger adapted to engage the plate and push it out of operative position, and key-controlled means for turning said plate.

7. In a lock, the combination of a casing, a gear inside the casing having a circular seat in one face thereof and a circular groove in the seat extending part way around it, a plate located in said seat having a pin thereon extending into the groove, whereby when the plate is turned it will turn the gear to a certain position, a key-receiving element having a bar adapted to engage and rotate said plate as the key is turned, and a spring for holding said plate in operative position, but permitting it to be moved from operative position.

8. In a lock, the combination with a casing, of a gear in the casing having a circular seat in its face, a plate located in said seat, means on the plate by which a motion of rotation imparted to it will be imparted to the gear throughout a portion of its rotation, said plate being displaceable so as to lose control of the gear, a plunger having a circumferential groove adapted to engage the plate and push it out of operative position, key-controlled means for turning said plate, and a spring-pressed holding arm adapted to enter said groove to normally prevent motion of the plunger.

9. In a lock, the combination with a casing, of a gear in the casing having a circular seat in its face, a circular plate located in said seat, means on the plate by which a motion of oscillation imparted to it will be imparted to the gear throughout a portion of its motion, said plate being displaceable so as to lose control of the gear, a plunger having a circumferential groove adapted to engage the plate and push it out of opera-

tive position, key-controlled means for turning said plate, and a spring-pressed holding arm adapted to enter said groove to normally prevent motion of the plunger, said gear having means on its surface for displacing said arm at each end of the oscillation of the gear so that the plunger can be caused to operate at that time only.

10. In a lock, the combination with a casing, of a gear in the casing having a circular seat in its face, a circular plate located in said seat, means on the plate by which a motion of rotation imparted to it will be imparted to the gear throughout a portion 50 of its rotation, said plate being displaceable so as to lose control of the gear, a plunger in position to engage the plate and push it out of operative position, key-controlled means for turning said plate, and means extending through the gear from the outside for displacing said plate and rendering it inoperative to turn the gear.

11. In a lock, the combination of a casing, a gear inside the casing having a circular seat in one face thereof and a circular groove in the seat extending part way around it, a plate located in said seat having a pin thereon extending into the groove, whereby when the plate is turned it will turn 70 the gear to a certain position, a key-receiving element, and a bar connected with said element and adapted to engage and rotate said plate as the key is turned.

12. In a lock, the combination with a casing, of a knob on one side of the casing, a gear in the casing fixed with respect to the knob and rotatable with it, said gear having a circular seat in its face, a plate located in said seat, and means by which a motion of 85 oscillation imparted to the plate will be imparted to the gear throughout a portion of its oscillation, said plate being displaceable so as to lose control of the gear.

13. In a lock, the combination with a casing, of a rotary member, a gear in the casing fixed with respect to the rotary member and rotatable with it, said gear having a cir-

cular seat in its opposite face, a plate located in said seat, means on the plate by which a motion of rotation imparted to it will be 55 imparted to the gear throughout a portion of its rotation, said plate being displaceable so as to lose control of the gear, and a circular bolt mounted in said casing to rotate on its own axis and to be operated by said gear.

14. In a lock, the combination with a casing, of a gear in the casing having a circular seat in its face, a plate located in said seat, means on the plate by which a motion 60 of rotation imparted to it will be imparted to the gear throughout a portion of its rotation, and a circular bolt mounted in said casing to rotate on its own axis and to be operated by said gear.

15. In a lock, the combination with a casing, of a gear in the casing having a circular seat in its face, a plate located in said seat, means on the plate by which a motion 70 of rotation imparted to it will be imparted to the gear throughout a portion of its rotation, key-controlled means for turning said plate, said casing having a circular projection inside constituting a bearing, and a circular bolt mounted to rotate on said bearing 75 having a radial slot therein for receiving a hasp and provided with teeth on the back for meshing with said gear so as to be operated by it.

16. In a lock, the combination with a casing having two cylindrical projections inside, each constituting a bearing, of two circular bolts each mounted to rotate on one of said bearings and located and guided solely thereby and each having a radial slot therein 85 for receiving a hasp and provided with a curved rack on the external circumference, and a single gear meshing with both of said racks for operating them so as to cause both slots in the bolts to enter a locking position 90 simultaneously.

In testimony whereof I have hereunto affixed my signature.

MORRIS FALK.
